ANTIBACTERIAL COMPOSITIONS

Herbert Quinn, Sycamore Township, Ohio, assignor to
The Procter & Gamble Company, Cincinnati, Ohio, a
corporation of Ohio
No Drawing. Filed Oct. 1, 1962, Ser. No. 227,584
1 Claim. (Cl. 167—30)

This invention concerns antibacterial compositions consisting of a mixture of antibacterial agents which exhibit enhanced antibacterial activity when used in combination with each other. More specifically this invention relates to a mixture of one or more commonly used bisphenol antibacterial agents as described more fully herein in combination with certain imino-imidazolidines, the mixture exhibiting enhanced antibacterial activity and particularly when incorporated into a soap, or detergent product formulation.

In recent years there has been a markedly increased usage of soaps and detergent products containing antibacterial agents by housewives and other consumers. This is due principally to the increased awareness by the consumer of the need to maintain and insure healthful living conditions. Many compounds have been suggested in past years for use as antibacterial agents in soaps, detergents, shampoos, and other surfactant based compositions; most of those compounds suggested, however, had some serious deficiencies which limited their utility. Such deficiencies were, for instance, ineffectiveness in soap solution, too great a toxicity, photosensitivity, and effectiveness only against a relatively narrow range of organisms. Additionally, many of the compounds suggested were only effective against bacteria when they were used in relatively large concentrations which made it impractical from a cost and formulation standpoint to incorporate them into a soap or detergent composition.

Some of these problems, particularly the cost problem, were alleviated somewhat by the discovery that certain binary combination of antibacterial agents exhibit synergism when admixed and incorporated into soap and detergent formulations. Synergistic combinations of antibacterial agents such as the halogenated bisphenols and halogenated carbanilides, halogenated bisphenols and the halogenated salicylanilides have been disclosed. The synergism or enhanced activity provides a higher level of antibacterial effectiveness for an equal amount of antibacterial agent used, or more important, it enables a manufacturer to use a lesser amount of antibacterial agents yet retain a relatively high degree of effectiveness, thereby enabling a less expensive product to be manufactured. This would be particularly helpful when the bisphenols are being used, as the discoloration of the soap caused by photosensitivity of this antibacterial agent is almost directly proportional to the amount of agent used, i.e., the higher the amount used, the greater the discoloration. It is significant to note that effective synergistic combinations of antibacterial agents or combinations which show enhanced activity are relatively rare and when such combinations are discovered, the synergism or enhancement is entirely unpredictable. It should be appreciated, therefore, that there is a need for still more effective antibacterial agents and combinations of agents having greater activity than has previously been known and which can be incorporated into soaps, detergent com-

2

positions and other formulations without substantial limitations.

It is therefore an object of this invention to provide antibacterial compositions having enhanced activity which possess a high level of antibacterial effectiveness.

It is a further object of this invention to provide antibacterial compositions which are effective in a soap or detergent product medium.

It is a still further object of this invention to provide antibacterial compositions which are economical and which do not have significant discoloration problems or toxicity problems.

Other objects and improvements will become apparent from the following description.

15 In accordance with this invention, it has been found that mixtures of (A) halogenated bisphenols and (B) substituted imino-imidazolidines, as hereinafter more fully described, exhibit enhanced antibacterial activity and particularly when incorporated into a fatty acid soap or 20 synthetic anionic, nonionic, ampholytic or amphoteric detergent composition at a ratio of (A) to (B) ranging from about 5:1 to about 1:5.

As used herein "enhanced" activity means antibacterial 25 activity that is greater than would be expected if the compounds acted independently when used as the same total percentage level.

The substituted bisphenols used in the mixtures described herein have the general formula:

30 where X is a halogen and n is an integer from 1 to 3 inclusive, and R is selected from the group consisting of alkylene radicals having from 1 to 4 carbon atoms and divalent sulfur.

40 Halogenated bisphenols which find utility in this invention are, for example, those disclosed in U.S. Patent 2,535,077, Kunz et al., and include bis-(2-hydroxy-3,5,6-trichloro phenyl)methane and bis-(2-hydroxy-3,5-dichloro phenyl)methane. Other suitable bisphenols include, for example, bis-(2-hydroxy-3,5,6-trichlorophenyl)-sulfide and bis-(2-hydroxy-3,5-dichlorophenyl)-sulfide.

45 The substituted imino-imidazolidine compounds used in the mixtures of this invention have the general formula:

50 where R is an alkyl radical having from 12 to about 18 carbon atoms and R' is selected from the group consisting of hydrogen, and alkyl radicals having from 1 to 6 carbon atoms.

55 60 These compounds are disclosed in U.S. Patent 2,999,047, Model et al. Those compounds which find particular usefulness are, for example, 1-dodecyl-2-imino-imidazolidine hydrochloride, 1-tetradecyl-2-imino-imidazolidine hydrochloride, 1-dodecyl-3-butyl-2-iminoimidazoli-

dine hydrochloride, 1-dodecyl-3-cyclohexyl-2-iminoimidazolidine hydrochloride, 1-tetradecyl-3-acetic acid-2-iminoimidazolidine hydrochloride, and 1-dodecyl-3-acetic acid-2-iminoimidazolidine hydrochloride.

The following combinations of antibacterial agents are illustrative of the mixtures of this invention possessing enhanced activity but should not be considered as limiting the scope of the invention.

Ratio of parts		5	Compound(s)	Total Anti-bacterial Agent(s) as Percent in BSD ¹	Ratio	Bacterial Colonies Surviving Per Sq. In. Cloth, <i>S. aureus</i>
A. IMD	.25					1,560
	.05					1,917
	.25					60
B. G-11	.125					1,117
	.1					1,171
	.05					1,792
C. IMD+G-11	.5			1:1		0
D. Detergent (Control)	.1			1:1		1,400
E. Water wash	.1					2,192
						2,142

¹ BSD-built synthetic detergent.

The built synthetic detergent used herein is composed of 17.5% alkylbenzene sulfonate, 50% sodium tripolyphosphate, and the balance substantially sodium sulfate.

It can be seen from the above example that the combinations of this invention surprisingly exhibit greater antibacterial effectiveness than would be expected if the compounds acted independently at the same total usage level. Such increased activity indicates that the combinations possess enhanced activity.

EXAMPLE II

In this example the enhanced activity of the combinations of this invention is shown by means of the "Standard Tube Dilution Test," which consists essentially of preparing serial dilutions of the antibacterial compositions to be tested in a FDA broth medium, inoculating with the chosen test organism and observing the weakest concentration which just prevents growth of the organism throughout incubation. This concentration (total quantity of antibacterial agent) is called the bacteriostatic breakpoint. In this in vitro test, the *Staphylococcus aureus* FDA 209 organism was used. Subsequent to the serial dilution of the antibacterial agent, 0.01 ml. of the organism is added to the tube containing the antibacterial agent after which the tube is incubated for 24 hours at 37° C., and thereafter the bacteriostatic breakpoint is determined.

In the following table the mixtures of antibacterial agents are in a 1:1 ratio and the following letters represent the compounds indicated:

IMD—1-dodecyl-2-iminoimidazolidine hydrochloride
G-11—bis(2-hydroxy-3,5,6-trichlorophenyl) methane

Bacteriostatic breakpoints ¹			
	Compound	Ratio	Total p.p.m. <i>S. aureus</i>
55	1. IMD		0.9
	2. G-11		0.11
	3. IMD/G-11	1:1	0.14 (EA) ²

¹ Expressed as p.p.m. total quantity of antibacterial agent required to inhibit growth of *S. aureus* organism.

²(EA) indicates enhanced activity.

It can be seen that enhanced activity is exhibited by the combinations shown.

Relatively small amounts of the enhanced antibacterial mixtures of the present invention are sufficient to render soap or detergent compositions antibacterially active. The soap or detergent composition can be in liquid, solid, flake, granular or other similar form. A soap or detergent composition is termed "antibacterial" if it is effective in killing or inhibiting the growth of the *Staphylococcus aureus* organism, whether or not it happens to be effective against any other type of bacteria.

Because of the enhanced activity of the mixtures of compounds of the present invention, it will be appreciated

EXAMPLE I

A convenient and meaningful method of measuring the antibacterial effectiveness of the enhanced mixtures of this invention is by means of the "Cloth Protection Test," H. Quinn, Applied Microbiology (Jan. 1962). Briefly, the test consists of washing cloth swatches in an aqueous solution containing the antibacterial agents to be tested, drying the swatches in a microorganism free atmosphere, and after drying, inoculating the swatch with a suspension of test organisms in serum (.1 ml. containing approximately 5000 organisms). After the inoculation with the serum suspension, the swatches are again allowed to dry and then they are planted in an agar medium Petri plate with the inoculated surface up and an overlay of nutrient is added over the fabric. The Petri plates are then incubated at 37° C. for 48 hours and thereafter bacterial counts are taken by means of a low-power dissecting microscope. The relative ability of a treated fabric to inhibit growth or kill the organism is the measure of the antibacterial activity of the particular agent or mixtures of agents being tested. In the table the lower number of colonies counted indicates the greater antibacterial effectiveness of the compound or mixture. Each figure represents an average of the organisms found on six replicate cloth swatches.

In this example the following letter abbreviations represent the compounds indicated.

IMD—1-dodecyl-2-iminoimidazolidine hydrochloride
G-11—bis(2-hydroxy-3,5,6-trichlorophenyl) methane

that smaller amounts than usual with conventional antibacterial agents can be incorporated into the soap or detergent compositions and still achieve good antibacterial effectiveness. Amounts as low as 1% of the enhanced mixtures described herein have proved satisfactory; however, it is preferred to use amounts of the mixtures ranging from 1% to 2% by total weight of the soap bar or detergent composition. The upper limit of the amount of agent to be used is determined by practical and economic considerations and is usually about 5%. The ratios of the agents listed under (A) and (B) supra can range from about 5:1 to about 1:5 with the preferred ratio being about 1:1.

Generally speaking, an increase in concentration of the mixture having enhanced activity increases the antibacterial effectiveness of the soap or detergent products. However, it is apparent that the cost of the agent in the soap, detergent composition, or other surfactant formulation mitigates against the use of an excessive amount. Additionally, if too large an amount is incorporated into the soap or detergent composition, the detergent properties of the product may be lessened.

The preferred antibacterial combinations which exhibit the most enhanced activity for use in this invention include bis-(2-hydroxy-3,5,6-trichlorophenyl) methane in combination with 1-dodecyl-2-iminoimidazolidine hydrochloride, and bis-(2-hydroxy-3,5,6-trichlorophenyl) sulfide in combination with 1-dodecyl-2-iminoimidazolidine hydrochloride, all at a 1:1 ratio.

The term "soap" as used herein is meant to designate alkali metal soaps such as sodium and potassium salts of the higher fatty acids of naturally occurring plant or animal esters (e.g., palm oil, coconut oil, babassu oil, soybean oil, castor oil, tallow, whale and fish oils, grease and lard, and mixtures thereof). Sodium and potassium soaps can be made by direct saponification of the fats and the oils or by the neutralization of the free fatty acids which are prepared in a separate manufacturing process.

The anionic synthetic detergent agent which can be employed with this invention is generally defined as a water soluble salt of an organic sulfuric reaction product having as its molecular structure an alkyl group containing from about 8 to about 22 carbon atoms and a radical selected from the group consisting of sulfonic acid and sulfuric acid ester radicals.

Important examples of the synthetics of this group which can be benefited through the incorporation therein of the mixtures of this invention, are the sodium or potassium alkyl sulfates, especially those derived by sulfation of higher alcohols produced by reduction of glycerides of tallow or coconut oil, sodium or potassium alkyl benzene sulfonates, especially those of the types described in U.S. Letters Patent 2,220,099, granted November 5, 1940, and 2,477,383, granted July 26, 1949, in which the alkyl group contains from about 9 to about 15 carbon atoms; sodium or potassium alkyl glyceryl ether sulfonates, especially those ethers in which the alkyl group is derived from the higher alcohols from tallow or coconut oil; sodium coconut oil fatty acid monoglyceride sulfates and sulfonates, sodium salts of sulfuric acid esters of the reaction product of one mole of a higher fatty alcohol (e.g., tallow or coconut oil alcohols) and about three moles of ethylene oxide, and others known in the art, a number being specifically set forth in Byerly, U.S. Letters Patent 2,486,921, granted November 1, 1949, and Strain, U.S. Letters Patent 2,486,922, granted November 1, 1949.

Additional anionic surface active sulfonates and sulfates which can be employed in this invention are the sulfated and sulfonated alkyl acid amides such as Igepon T ($C_{17}H_{33}CON(CH_3)CH_2CH_2SO_3Na$), the sulfated and sulfonated esters such as Igepon AP ($RCOOCH_2CH_2SO_3Na$) where R is an alkyl radical containing from 11 to 17 carbon atoms) sodium salt of the bisulfate of a dialkyl dicarboxylate, sodium salt of the sulfonic acid derivative of a dialkyl dicarboxylate, sodium sulfosuccinic esters such as $NaOOCCH_2CH(SO_3Na)CONHC_{18}H_{37}$ and the like.

A minor amount, totaling about 2% of a 1:1 mixture of bis-(2-hydroxy-3,5,6-trichlorophenyl) methane and 1-dodecyl-2-imino-imidazolidine hydrochloride for example, renders a composition containing any of the above detergents or mixtures thereof, antibacterially active against the common organisms found on the skin.

The nonionic synthetic organic detergents which have utility in the practice of this invention may be broadly defined as compounds produced by the condensation of alkylene oxide groups (hydrophilic in nature) with an organic hydrophobic compound, which may be aliphatic or alkyl aromatic in nature. As those skilled in the art are well aware, the length of the hydrophilic or polyoxyalkylene radical required for condensation with any particular hydrophobic group can be readily adjusted to yield a water-soluble compound having the desired degree of balance between hydrophilic and hydrophobic elements.

For example, a well known class of nonionics is made available on the market under the trade name of "Pluronic." These compounds are formed by condensing ethylene oxide with a hydrophobic base formed by the condensation of propylene oxide with propylene glycol. The hydrophobic portion of the molecule, of course, exhibits water insolubility. Its molecular weight is of the order of 1500 to 1800. The addition of polyoxyethylene radicals to this hydrophobic portion tends to increase the water solubility of the molecule as a whole. Liquid products are obtained up to the point where polyoxyethylene content is about 50% of the total weight of the condensation product.

Suitable nonionics also include the polyethylene oxide condensates or alkyl phenols, e.g., the condensation products of alkyl phenols having from 6 to 12 carbon atoms, either straight chain or branch chain, in the alkyl group with ethylene oxide in amounts equal to 10 to 25 moles of ethylene oxide per mole of alkyl phenol. The alkyl substituent in such compounds may be derived from polymerized propylene, diisobutylene, octane, or nonane, for example.

Other suitable nonionics may be derived by the condensation of ethylene oxide with the product resulting from the reaction of propylene oxide and ethylene diamine. Here again, a series of compounds may be produced, depending on the desired balance between hydrophobic and hydrophilic elements. For example, compounds (molecular weight from about 5,000 to about 11,000) of about 40% to 80% polyoxyethylene content and resulting from the reaction of ethylene oxide groups with a hydrophobic base constituted of the reaction product of ethylene diamine and excess propylene oxide, said base having a molecular weight of the order of 2500 to 3000, are satisfactory.

Further satisfactory nonionics include the condensation product of aliphatic alcohols having from 8 to 18 carbon atoms, either straight chain or branch chain, with ethylene oxide, an example being a coconut alcohol ethylene oxide condensate having from 10 to 30 moles of ethylene oxide per mole of coconut alcohol, the coconut alcohol fraction having from 10 to 14 carbon atoms.

The amphotolytic surface-active detergents which can be used in the practice of this invention have the general formula RZX where R is an aliphatic hydrophobic group containing from about 8 to about 18 carbons, X is an anion selected from the group consisting of sulfonate, sulfate and carboxy radicals, Z is an intermediate group jointed to R by a member of the group consisting of ether, polyether, ester, amide and amine linkages, and M is a cation to neutralize the charge of the anion. Classification according to whether the detergent has an intermediate linkage or not is used in "Surface Active Agents and Detergents," by A. M. Schwartz, J. W. Perry, and J. Berch, Interscience Publishers, New York, 1958, vol. II.

Examples of amphotolytic compounds are disodium lauryl beta-iminodipropionate, dipotassium lauryl beta-iminodipropionate and alkyl beta-iminopropionate, where the

alkyl group is derived from the middle cut or coconut alcohol or fatty acid.

Other detergent compounds which can be used in the practice of this invention include the amphoteric sulfated and sulfonated quaternary ammonium compounds known as sultaines or sulfo-betaines. These compounds are described in U.S. patent application No. 163,042 and can be prepared in the manner disclosed in U.S. Patent 2,129,264 and German Patent 1,018,421. Specific examples are 3-(N,N-dimethyl-N-hexadecyl ammonio)-2-hydroxypropane-1-sulfonate, 3-(N,N-dimethyl-N-alkyl ammonio)-2-hydroxypropane-1-sulfonate, the alkyl group being derived from tallow alcohol, 3-(N,N-dimethyl-N-dodecylammonio)-propane-1-sulfonate, and 3-(N,N-diethyl-N-hexadecyl ammonio) propane-1-sulfonate.

The enhanced mixtures of this invention have been found to increase the antibacterial activity of soap and non-soap synthetic detergent compositions in bar, liquid, flake, granular and other forms and can be incorporated into the soap or detergent composition by any suitable method preferably which yields as a result a uniform distribution of agents throughout the whole mass.

Regular use of a "Camay" or "Ivory" type soap bar containing 1.5% of the mixtures of this invention possessing enhanced activity, e.g., 1% bis(2-hydroxy-3,5,6-trichlorophenyl) methane plus .5% 1-dodecyl-2-iminoimidazolidine hydrochloride results in substantial reductions in the bacterial population of the skin and thereby markedly reduces body odor attributable to the bacterial degradation of perspiration. (Camay and Ivory are mixtures of potassium and sodium tallow and coconut oil soap.)

A sample formula for a milled toilet detergent bar which can be prepared by means known and used in the art is as follows (the term "middle-cut" as used herein refers to that fraction of distilled coconut alcohol which consists predominantly of lauryl and myristyl alcohols):

20.5% potassium alkyl sulfate (alkyl group derived from the middle cut of alcohols obtained by the catalytic reduction of coconut oil)
 8.0% sodium alkyl glyceryl ether sulfonate (alkyl group derived from the middle cut of alcohols obtained by catalytic reduction of coconut oil)
 33.81% sodium soap of 20:80 coconut:tallow fatty acids
 17.07% magnesium soap of 20:80 coconut:tallow fatty acids
 5.81% inorganic salts
 .75% bis(2-hydroxy-3,5,6-trichlorophenyl) methane
 .50% 1-dodecyl-2-iminoimidazolidine hydrochloride
 8.0% moisture
 Balance miscellaneous

This bar exhibits good odor reducing properties and reduces the numbers of bacteria on the skin and does not discolor significantly.

A granular built synthetic detergent composition having the following formulation can be prepared by spray drying and the antibacterial agents of this invention can be incorporated therein. This composition imparts considerable antibacterial activity to fabrics washed in the solution.

10 17.5% sodium alkyl benzene sulfonate (the alkyl radical averaging about 12 carbon atoms and being derived from polypropylene)
 47.9% sodium tripolyphosphate
 15 13.3% sodium sulfate
 7.0% silicate solids
 .75% bis(2-hydroxy-3,5-dichlorophenyl) methane
 .75% 1-tetradecyl-2-iminoimidazolidine
 Balance water and miscellaneous

20 The invention has been described above in conjunction with various illustrative examples of antibacterial compositions, toilet and laundry detergents. It will be obvious to those skilled in the art, however, that the antibacterial mixtures can also be beneficially employed in such products as shampoos, antiseptic ointment, foot powders, and the like.

What is claimed is:

30 An antibacterial composition comprising a combination of (A) bis(2-hydroxy-3,5,6-trichlorophenyl) methane and (B) 1-dodecyl-2-iminoimidazolidine hydrochloride, the proportions by weight of (A) and (B) being about 1:1, said combination displaying a synergistic antibacterial action 35 when used with water from a medium in which the concentration of the said combination ranges from about 0.1% to about 0.5% by weight.
